Inventor:
John L. Hyland

UNITED STATES PATENT OFFICE

JOHN L. HYLAND, OF NEW YORK, N. Y.

BULKHEAD DOOR

Refile of abandoned application Serial No. 158,124, filed December 28, 1926, and Serial No. 390,003, filed June 18, 1920, respectively. This application filed November 26, 1928. Serial No. 322,282.

This invention relates to certain new and useful improvements in doors and primarily to bulkhead doors and also building doors.

An object is to provide a bulkhead door which will be always watertight, airtight and fireproof and which will serve effectively as a forced draft door.

A further object is to provide a vertically swinging bulkhead door by which coal, ashes, and the like may be transferred from one compartment to another through the intervening bulkhead and yet always maintain a fireproof and water-tight partition therebetween.

The invention still further resides in a door for the purpose of ventilation, the same being applicable to bulkheads or buildings.

In the drawings:—

Fig. 1 is a fragmentary elevation of the bulkhead equipped with my improved door;

Fig. 2 is a horizontal section therethrough showing both doors fully closed;

Fig. 3 is a similar view showing the doors closed within their frames but spaced apart to permit ventilation of the compartments;

Fig. 4 is a like view showing one door fully closed and the companion door fully opened to permit the entrance or exit of seamen;

Figs. 5 and 6 are vertical sections through bulkhead doors mounted to swing on horizontal pivots, and

Fig. 7 is a sectional view showing the invention as applied to doors of buildings and dwellings.

Referring more in detail to the drawings, the bulkhead 1 is provided with a doorway 2 on the opposite sides of which are arranged watertight frames, each comprising a top wall 3 and an arcuate side wall 4 in which may be provided a window or ventilating opening 5.

Two doors are provided for each doorway, being mounted on opposite sides thereof by the vertical pivots 7 for swinging horizontally, their free vertical and top edges wiping the arcuate side and top walls, respectively, of the watertight frames. The doors are flexibly connected by the cross chains 8, each being connected at one end to the inner portion of one door and at its opposite end

to the outer portion of the companion door, whereby when one door is pulled open the other door will be pulled closed against the jamb or seats 9 which may be provided with suitable facing to effect a watertight, airtight and fireproof joint. With both doors fully closed or seated, as in Fig. 2, they are airtight, whereas in Fig. 3 they are separated but still disposed within their respective frames to provide ventilation from one window 5 through the other window on the opposite side of the bulkhead. To enter between the doors the farther door will automatically close when the nearer is pulled open, as in Fig. 4.

Figs. 5 and 6 disclose bulkhead doors 10 mounted to swing on horizontal pivots 11 within frames 12 having segmental end walls and arcuate top walls. On one side of the bulkhead is disposed a bracket 13 for supporting the adjacent door at an upward inclination whereby coal may be deposited thereon and easily swung to vertical position.

Where forced draft is used, the doors prevent back fire which accidentally occurs when the ordinary door is left opened. Ventilation may be readily obtained by separating the doors within their frames from which position the doors will automatically close when fluid or liquid pressure acts exteriorly thereof. When fully closed, it will be noted that the doors are located between the windows to close communication therebetween. The same principle is applied to doors of dwellings and other buildings, as exemplified in Fig. 7 wherein a special jamb 20 is designed to have the door 21 to interlock therewith at one or more points to permit more or less ventilation through the opening 22. The interlocking engagement is such that fluid pressure may act thereon to move it to fully closed position.

In constructions where the ventilating windows are omitted the doors are always airtight. Thus, as depicted in Fig. 3, the doors may be separated and still provide an airtight, watertight and fireproof closure as well as when the doors are fully closed.

The end walls of the frame may be connected directly to the doors, as in Figs. 5 and

6, providing pockets for the efficient handling of coal and ashes.

In any form, the doors provide watertight closures between compartments and yet permit the ready passage of seamen from one compartment to the other. The chains which connect the doors may be omitted in the embodiment shown in Figs. 5 and 6, since the end walls serve to connect the doors and brace them apart.

What is claimed is:—

1. An airtight, watertight and fireproof bulkhead closure comprising a pair of doors hinged on opposite sides of a bulkhead, chains connecting the doors whereby opening one door will close the other, and watertight frames housing the free edges of the doors, said frames provided with ventilating openings on opposite sides of the bulkhead and said doors adapted to separate within their frames to include the ventilating openings.

2. A door frame having a ventilating opening, and a door mounted in the frame to be secured on either side of the opening to either open or close ventilation.

3. An airtight, watertight and fireproof bulkhead closure including in combination with a bulkhead having an opening, a pair of doors hinged at one side on opposite sides of the opening, frames on opposite sides of the opening projecting outwardly from the bulkhead and each composed of a top wall and an arcuate side wall, the arcuate side walls being formed to have watertight engagement with the opposite free sides of the doors, and means connecting the doors whereby opening of one door will close the other.

4. An airtight, watertight and fireproof bulkhead closure including in combination with a bulkhead having an opening, a pair of doors hinged at one side on opposite sides of the opening, frames on opposite sides of the opening projecting outwardly from the bulkhead and housing the opposite free sides of the doors, said frames having ventilating openings on opposite sides of the bulkhead, the doors being movable to lie outwardly beyond said ventilating openings, and means to connect the doors whereby opening of one door will close the other.

5. An airtight, watertight and fireproof bulkhead closure including in combination with a bulkhead having an opening, a pair of doors hinged at one side on opposite sides of the opening, frames on opposite sides of the opening projecting outwardly from the bulkhead and formed to engage the opposite free sides of the doors, and means whereby opening of one door will close the other.

6. An airtight, watertight and fireproof bulkhead closure including in combination with a bulkhead having an opening, a pair of doors hinged at one side on opposite sides of the opening, frames on opposite sides of the opening projecting outwardly from the bulk-

head and having arcuate portions formed to engage the opposite free sides of the doors, and means whereby opening of one door will close the other.

7. In combination with a bulkhead having a doorway, a pair of doors hinged at one side to swing on the respective opposite sides of the bulkhead, a watertight frame, for each door having an arcuate portion to engage the opposite free side of the doors, said arcuate portions extending outwardly from opposite sides of the bulkhead, and means whereby opening of one door will close the other.

In testimony whereof I affix my signature.

JOHN L. HYLAND.
